PACKAGE FOR BOTTLES

Charles K. Ellsworth, Detroit, Mich.

Application September 11, 1933, Serial No. 688,964

9 Claims. (Cl. 229—27)

The present invention pertains to a novel box adapted to contain a number of bottles in a neat package. The box is made of suitable stiff material such as heavy paper or cardboard corrugated on one or both faces and having heat insulating properties.

The principal object of the invention is to form a container from a blank of stock in a single die cut operation and with practically no waste of material. Further, it is desired to hold the bottles against rattling and to provide insulation between the bottles. These several objects are accomplished according to the invention by a novel arrangement in the scoring, cutting and folding of the blank.

The invention is fully disclosed by way of example in the following description and the accompanying drawing, in which:—

Figure 1 is a plan view of the blank, showing the inner face thereof;

Figure 2 is a plan view of the body of the box, showing also the arrangement of bottles therein;

Figure 3 is a section on the line 3—3 of Figure 2;

Figure 4 is a perspective view of the box in inverted position to show the construction of one of the sides;

Figure 5 is a section on the line 5—5 of Figure 2, and

Figure 6 is an end view of the box, showing the position of the flaps just before insertion.

Reference to these views will now be made by use of like characters which are employed to designate corresponding parts throughout.

The box is made of a rectangular blank of material having suitable stiffness, such as heavy paper or cardboard which is preferably corrugated on the outer surface, although both faces may be flat if desired. The blank is designated generally by the numeral 1, and the corners at one end are knocked out as indicated by the numeral 2, for a purpose which will presently be described.

A single die cut operation performs the various operations which will now be described including also the knocking out of the corners 2. The blank is scored lengthwise along two lines 3 near the longitudinal edges and again along lines 4 between said edges and the line 3. The blank is also scored transversely on two lines 5 substantially midway between the ends, along a transverse line 6 joining the transverse edges of the knocked-out portions 2, and finally along a transverse line 7 spaced inwardly from the line

6 a distance approximately equal to the spacing between the lines 5.

Parts of the lines 3 together with one of the free edges 8 of the blank and one of the lines 5 form a rectangle 9 which constitutes the top of the box. Similarly, parts of the lines 3 together with parts of the line 7 and one of the lines 5 form a rectangle 10 which constitutes the bottom of the box. The blank is also cut through along parts of the scored lines. The cut parts are illustrated by solid lines, and the parts remaining scored are shown by broken lines. The blank is cut in continuation of the lines 5 and 7 from the lines 3 outwardly to the adjacent edges, as indicated by the numeral 11, forming tongues 12 and 13 respectively. The rectangular piece 14 enclosed by parts of lines 5 and 3, and the similar rectangular piece 15 enclosed by parts of lines 6, 7 and 3 form the end walls. The rectangular pieces 16 formed each by parts of line 3 and 4, the cuts 11 and free edge 8 constitute side covers carried by the top 9. The marginal pieces 17 outward of the parts 16 and defined each by a part of a line 4, cut 11, edge 8, and the longitudinal edges of the blank constitute flaps to be tucked into the body of the package to hold the covers closed, as will presently be described.

Between the line 7 and the nearer line 5, spaced cuts 18 are formed in each line 4. The cuts are preferably equal in length to the spacing therebetween, and the cuts on one of the lines 4 are preferably staggered with relation to those on the other line 4 as may clearly be seen in Figure 1. Finally, a cut 19 is taken from one end of each cut 18 perpendicularly to the nearer longitudinal edge. The tabs 20 thus formed obviously remain united to the blank along the uncut parts of the lines 4. A hole 21 of sufficient size to receive the neck of the bottle is cut in each tab 20 with its center on the normal to the line of union of the tab. Also, the outer corners of the flaps 17 are preferably knocked off as indicated by the numeral 22. The bottom section 10 is punched at 23 at the midpoints of the lines 3 thereon, for a purpose to be described below.

With reference to the assembly of the box, it will be evident that the blank can readily be folded along the scored lines. The particular order of folding is optional, and the sequence presently to be described is merely illustrative. The blank is first folded inwardly on lines 3 at the bottom 10 to bring the marginal parts into contact with the bottom. These marginal parts are then folded back along lines 4 to bring the tabs into a ver-

tical position. The strips 23 between lines 3 and 4 and coextensive with the bottom remain in contact with the bottom as shown in Figure 5.

The tabs 20 are of various lengths, some being 5 extended from one end of the line of union, some from both ends and some from neither end. These extended or overhanging parts are turned inwardly as indicated by the numeral 24 in Figure 2. The arrangement of the overhanging parts 24 10 with respect to the several tabs is also optional and is governed somewhat by the number of bottles to be accommodated in the package. It will also be evident from Figure 2 that the necks 15 of bottles 25 can be inserted in the holes 21, the bottles lying on the bottom 10 and being arranged in successively inverted positions. After the overhanging parts 24 of tabs are turned inward as illustrated, there is no obstruction to the insertion of a bottle across an edge of the box 20 and into a hole 21.

The blank is then folded inward successively on the lines 7 and 6 whereby the piece 15 assumes a vertical position and becomes an end wall as shown in Figure 3. The piece 26 between the line 6 and the adjacent free edge becomes an end flap lying horizontally over one of the end bottles as also shown in Figure 3. The square pieces 27 defined by the lines 3 at the ends of the flap 26 are turned downward in opposition to the ends of 30 one of the end bottles as shown in Figures 2 and 5. This condition is also shown in Figure 4 wherein the box is inverted for better illustration. The tongues 13 at the ends of the end wall 15 are also turned inwardly outside of the 35 pieces 27.

The blank is then folded successively on the lines 5 so that the strip 14 assumes a vertical position as an end wall. The tongues 12 at the ends of the wall 14 are turned inward alongside the 40 edges of the bottom 10.

When a right-angle bend has been made on each line 5, the top 9 lies over the bottles as in Figure 6, the outer edge 8 of the top piece overlapping the flap 26. Folds are taken on the lines 3 and 45 4, alongside the top 9, bringing the strips 16 into position as side covers at the ends of the bottles and leaving marginal flaps 17 which are conveniently tucked into the package in surface contact with the overlaid strips 23 and beneath 50 the tongues 12, 13 and 27.

The corrugations of the part 17 interlock with the corrugations of part 23, thereby increasing the rigidity of the box, against wobbling, for a given thickness of material. Also, the corrugations provide an increased area of friction contact between each flap 17 and part 23.

The holes 28 form semi-circular thumb openings along the edges of the bottom section to facilitate engaging the flaps 17 to pull them out in opening the box. Further, these holes facilitate handling the packages in removing them individually from a case consisting of a number of packages.

It will now be seen that the box is made from 65 a simple rectangular blank of stock in a single die-cut operation and with practically no waste of material. In this connection, particular reference is made to the tabs 20. Although only the square parts thereof having the holes 21 appear to be necessary for positioning the bottles, the overhanging parts 24 nevertheless serve a very useful purpose as insulation and padding between bottles. As shown in Figure 2, the parts 70 24 are so inserted between bottles as to prevent clattering by contact of glass to glass, and the

insulating property of the material retards the rate of temperature change.

The filled bottles may be inserted in the box before the sale to the retailer, and in the preferred use of the box, the wholesaler or distributor ships the merchandise in the form of cases consisting each of several filled boxes superimposed one upon the other. Several advantages result from this method. First, the probability of breakage in transit is materially reduced. Second, the retailer finds it convenient to unpack the shipment and put it away in his storage room or refrigerator since he handles the merchandise in the form of packages containing a salable number of bottles, such as three, six or twelve. Finally, the speed of making a sale of such a number of bottles to consumer is increased, as the retailer need only take a package from this refrigerator and hand it to the customer. Even wrapping is not necessary inasmuch as the exterior of the box 20 may be attractively finished.

The customer places the package, with one end open, in a refrigerated compartment. The box itself furnishes sufficient insulation to maintain the contents in a chilled condition until the customer arrives at his destination where he either consumes the contents forthwith or places the package in the refrigerator. The possession of the empty box encourages return of the empty bottles which can conveniently be replaced and carried in the box.

Although specific embodiments of the invention have been illustrated and described, it will be understood that various alterations in the details of construction may be made without departing from the scope of the invention as indicated by the appended claims.

Having thus fully disclosed my invention, what I claim and desire to secure by Letters Patent is:

1. A box comprising a blank of material having marginal portions at opposite edges of the blank standing perpendicular to the original plane of the blank, said portions being apertured to receive bottle necks, the apertures in one of said portions being staggered relatively to those in the other portion, parts of said blank being formed to enclose said marginal portions.

2. A box comprising a blank of material having marginal portions standing perpendicular to the original plane of the blank, said portions being apertured to receive bottle necks, certain of said portions being folded toward the opposite margin at a right-angle and on an axis perpendicular to said original plane, parts of said blank being formed to enclose said marginal portions.

3. A box comprising a substantially rectangular blank foldable transversely to form a top and bottom with an end wall therebetween, side walls at the edges of said top extending from the end wall, overlaid sections at opposite edges of the bottom in line with the side walls and doubled over to lie upon said bottom, tabs formed at the outer edges of said sections and standing perpendicular to said bottom, said tabs being apertured to receive bottle necks, another end wall formed at the remaining end of the bottom, tongues at the ends of said end walls and extending alongside of said overlaid sections, and flaps at the edges of the side walls and adapted for insertion between said sections and tongue respectively.

4. A box as characterized in claim 3, the overlaid sections being of the same width as the side walls, and the tongues being of the same width as said tabs.

5. A box as characterized in claim 3, said

tabs being severed from said overlaid sections except directly below said apertures, the severed parts being folded inwardly toward the opposite edge of the bottom, whereby to lie between adjacent bottles.

5. A box as characterized in claim 3, said tabs being severed from said overlaid sections except directly below said apertures, the severed parts being folded inwardly toward the opposite edge of the bottom, whereby to lie between adjacent bottles, the apertured parts along one edge being staggered in relation to those at the other edge.

10. A box as characterized in claim 3, having

another flap extending from the last-named end wall and adapted to lie beneath the free end of said top.

8. A box as characterized in claim 3, the overlaid sections being of the same width as the side walls, and the tongues being of the same width as said tabs, and another flap extending from the last-named end wall and adapted to lie beneath the free end of said top.

9. A box as characterized in claim 3, the outer surfaces of said blank and parts formed therefrom being corrugated.

CHARLES K. ELLSWORTH.
